UNITED STATES PATENT OFFICE.

CHARLES H. BELL, OF THOMASTON, CONNECTICUT, ASSIGNOR TO SETH THOMAS CLOCK CO., OF THOMASTON, CONNECTICUT, A CORPORATION.

KEYLESS CLOCK.

1,087,076.

Specification of Letters Patent.

Patented Feb. 10, 1914.

Application filed April 5, 1913. Serial No. 759,161.

To all whom it may concern:

Be it known that I, CHARLES H. BELL, a citizen of the United States, residing at Thomaston, in the county of Litchfield and 5 State of Connecticut, have invented a new and useful Improvement in Keyless Clocks; and I do hereby declare the following, when taken in connection with the accompanying drawings and the characters of reference 10 marked thereon, to be a full, clear, and exact description of the same, and which said drawings constitute part of this application, and represent, in—

Figure 1 a view in front elevation of a keyless clock constructed in accordance with 15 my invention. Fig. 2 a view thereof in side elevation. Fig. 3 a view of the clock-case in central, horizontal section on the line *a—b* of Fig. 1, with the clock-movement shown 20 in plan. Fig. 4 a view of the clock in front elevation with the bezel and dial removed. Fig. 5 a detached edge view of the clock-movement. Fig. 6 a view of the clock in 25 front elevation with the bezel, winding-and-setting ring and dial removed, the parts being shown in their normal or winding positions. Fig. 7 a corresponding view with the parts in their setting positions, with the centering brige removed. Fig. 8 a view in 30 rear elevation of the front movement-plate, showing the levers employed for shifting the parts from their winding to their setting positions. Fig. 9 a perspective view in rear elevation, of the rotary winding and setting 35 plate. Fig. 10 a detached perspective view of the centering bridge. Fig. 11 a corresponding reverse view thereof. Fig. 12 a detached perspective view of the sliding setting-arm. Fig. 13 a corresponding view of 40 the bell-crank lever carrying the intermediate gear.

My invention relates to an improvement in keyless clocks of the type primarily designed for use as automobile clocks, though 45 not limited to such, the object being to produce a simple, convenient, reliable and durable keyless clock constructed with particular reference to centering its winding and setting gear member upon the movement itself rather than upon the case as heretofore, so as to reduce the wear and strain of winding and setting to the minimum, as well as the danger of breakage or derangement owing to the lateral displace-

ment in use of the winding and setting 55 member gear with respect to the elements of the winding and setting trains.

With these ends in view, my invention consists in a keyless clock having certain details of construction and combinations of 60 parts as will be hereinafter described and pointed out in the claims.

In carrying out my invention, as herein shown, I employ a rotary winding and setting gear member in the form of a circular 65 plate 2 having a large concentric opening receiving the flange 3 of an annular external gear 4 projecting from the inner face of the said plate with which the gear rotates. The said gear 4 sets over and has rotary bearing 70 upon a large circular bearing-and-positioning hub 5 centrally located with respect to the clock-movement and formed upon the outer face of a specially constructed centering-bridge 6 secured by screws 7 to the outer 75 face of the front movement-plate 8 of the clock. The said hub 5 is formed with a central opening 9 for the reception of the sleeve 10 of the hour-wheel 11, the center-arbor 12 projecting forward through the said sleeve. 80 Upon its inner face the hub 5 is formed with a recess 13 for the clearance of the hour-wheel 11 and with a recess 14 for the clearance of the minute-wheel 15 and the pinion 16 thereof. The centering-bridge 6 is also 85 formed with a circular opening 17 for the clearance of the seconds-staff 18 which projects forward through it as shown in Fig. 4.

Under the construction above described, the large centrally located hub 5 of the 90 bridge 6 constitutes a fixed bearing for the circular winding and setting plate or gear member 2 which is thus carried by and centered with respect to the clock-movement rather than by the cylindrical band 19 of 95 the clock-case which has been used heretofore to center the winding and setting gear members of keyless clocks of the type to which my improvement belongs. The said plate 2, as shown, is formed with a circular 100 series of segmental slots 20 arranged to expose the regulator arbor 21 which may be squared for the reception of a key, or which may be provided, as shown, with a hub 22 having an operating arm 23. In case, in 105 the operation of the plate 2, none of its slots 20 stand over the arbor 21, when the plate comes to a rest, the plate may be

slightly shifted in one direction or the other so as to afford access to the arbor 21 through one of the slots 20.

For the rotation of the winding-and-setting plate 2, it is provided, as shown, with three equi-distant radial coupling-arms 24 adapted to enter coupling-slots 25 (Fig. 9) formed in the edge of the forwardly projecting externally threaded flange 26 of a rotary knurled winding and setting ring 27 which is centered upon the forward edge of the case-band 19. The said ring 27 is held against forward movement upon the case-band 19 by the radial coupling-arms 24 of the plate 2 which is itself held against lateral movement by being interposed between the outer face of the centering-bridge 6 and the inner face of the dial 28 which is secured by means of screws 29 directly to the flat outer face of the hub 5 of the bridge 6. The ring 27 is prevented from moving rearwardly upon the case-band 19 by the bearing upon the outer face of the dial 28, of the dial-mat 30 which rides upon the dial 28 and which, together with the crystal 31, is located within the bezel 32 which is formed with a knurled rim 33 and provided with internal threads for being screwed upon the forwardly projecting externally threaded flange 26 of the said ring 27 which thus carries the bezel 32 and is turned by the same. The plate 2 is thus seen to be centered upon the hub 5 of the winding-bridge 6 and coupled with the bezel 32 by means of which it is rotated in one direction or the other, through the medium of the ring 27, which has bearing upon the band 19 of the clock-case. I prefer to make the plate 2 sufficiently smaller than the internal diameter of the ring 27 to provide an accommodation space 34 (Fig. 4) sufficiently large to permit the clock-movement to accommodate itself in position within the clock-case so as to avoid any binding of the ring 27 upon the case-band 19, whereby the ring 27 may be fitted sufficiently closely upon the caseband 19 to prevent the entrance of dust and dampness into the movement without endangering the binding of the parts should the movement not be accurately centered within the clock-case. In that event the plate 2 would be free to move laterally in the annular accommodation space 34 to an extent sufficient to compensate for the want of concentricity between the ring 27 upon the case-band 19 and the center of the movement within the clock-case.

The external gear 4 carried by the rotary winding and setting plate 2, is normally maintained in mesh with an intermediate winding-and-setting wheel 35 turning upon a stud 36 mounted in the arm 37 of a bell-crank lever 38 bearing against the inner face of the front movement-plate 8 and

swinging upon a screw 39 as shown in Fig. 3, the said plate 8 being formed with a slot 40 through which the stud 36 extends outward for the carriage of the wheel 35 which bears upon the outer face of the said plate 8 and normally meshes into the main winding or ratchet wheel 41 which is mounted upon a square winding-arbor 42 held against reverse rotation by an ordinary ratchet pawl 43 operated by a spring 44. The arm 45 of the bell-crank lever 38 is engaged by a spring 46 mounted upon the inner face of the front movement-plate 8 and exerting a constant effort to swing the bell-crank lever 38 so as to maintain the wheel 35 in constant mesh with the main winding or ratchet wheel 41, to provide for what is commonly known as "ratcheting back." The bell-crank lever aforesaid forms a swinging carrier for the winding and setting wheel 35.

For setting the clock, I provide a flat, sheet-metal sliding setting-arm 47 arranged to bear upon the inner face of the front movement-plate 8 to which it is secured by means of studs 48, 49, respectively, passing through a slot 50 in its outer end, and a slot 51 in its inner end, the arm being given an outwardly bowed form for the purpose of clearance. At its outer end the said arm 47 has a finger 52 co-acting with the inner end of a plunger 53 having its outer end provided with a button 54 the inner end of which extends over a sleeve 55 projecting radially from the case-band 19 and forming a bearing for the plunger 53. At its inner end the setting-arm 47 is formed with a rounded nose 56 engaging with the outer end of the arm 37 of the bell-crank lever 38. When the button 54 is pressed inward so as to overcome the tension of the spring 46, the bell-crank lever 38 swings upon its screw 39, whereby the wheel 35 is demeshed from the main-winding wheel 41 and moved into mesh with an intermediate setting-wheel 57 mounted on a stud 58 projecting from the outer face of the front movement plate 8 and carrying upon its inner face a wheel 59 meshing into the minute-wheel 15. As long as inward pressure is maintained upon the button 54, the parts of the clock will be in position for setting, which will be effected by turning the bezel 32 in one direction or the other without, however, imparting any lateral or forward or back movement to it. The moment inward pressure upon the button 54 is removed, the spring 46 will assert itself to swing the bell-crank lever 38 so as to carry the wheel 35 out of mesh with the wheel 57 and into mesh with the main winding wheel 41, leaving the clock-movement again in normal readiness for winding.

The clock-movement proper may be of any approved construction, and no detailed description of it is called for. As shown it

is formed with a rear movement-plate 60 connected with the front movement-plate 8 by means of pillars 61. The entire movement is mounted within the case-band 19 by means of heavy pillars 62 screwed at their forward ends into the plate 60 and having their rear ends threaded for the reception of screws 63 passing from rear to front through the case-back 64 which is fitted 10 snugly within the rear end of the circular case-band 19.

What I particularly wish to emphasize in connection with my improvement is that the winding and setting gear is centered entirely with respect to the clock-movement rather than with respect to the clock-case, whereby I secure a greater accuracy of mesh as well as a greater freedom of operation than can be achieved where the winding-and-setting gear is centered upon the case rather than upon the movement.

I claim:—

1. In a keyless clock, the combination with a clock-case, of a time-movement having movement plates and winding-and-setting trains, a bearing and positioning hub located upon one of the said movement-plates concentric with the center shaft of the said movement and smaller in diameter than the 30 plate on which it is located, a winding-and-setting gear having bearing upon the said hub by which it is centered with respect to the movement, and a rotary winding-and-setting member concentric with and centered 35 upon the said clock-case and connected with the said gear for driving the same.

2. In a keyless clock, the combination with a case, of a time-movement having winding and setting trains, a centering-bridge 40 mounted upon one of the plates of the said time-movement and provided with a bearing and positioning hub concentric with the center-shaft of the said movement, a rotary winding-and-setting plate turning upon the 45 said hub and carrying a gear co-acting with

the winding and setting trains of the said movement, and a rotary bezel centered upon the clock-case and connected with the said plate for the operation thereof, whereby the said winding-and-setting plate and gear 50 are centered and positioned by the time-movement rather than by the case.

3. In a keyless clock, the combination with a case, of a time-movement having winding and setting trains, a centering-bridge fixed 55 to the movement and provided with a bearing and positioning hub concentric with the center-shaft of the said movement, a winding-and-setting plate having rotary bearing upon the said hub and provided with an annular gear co-acting with the winding and setting trains of the movement, and a rotary bezel bearing upon the clock-case, the said plate and bezel being coupled together with capacity for accommodation with respect to 60 each other, whereby the said plate is centered and positioned by the movement rather than by the case.

4. In a keyless clock, the combination with a clock-case, of a time-movement having 70 winding and setting trains, a centering-bridge fixed to the movement and having a bearing and positioning hub, a dial fixed to the said bridge, a circular winding-and-setting plate having bearing upon the said hub, 75 interposed between the said bridge and dial and provided with an annular gear co-acting with the winding and setting trains of the clock, and a rotary bezel mounted upon the clock-case and coupled with the said plate 80 which it rotates, whereby the said plate is centered and positioned by the movement rather than by the case.

In testimony whereof, I have signed this specification in the presence of two subscribing witnesses.

CHARLES H. BELL.
